valve is in closed position. On this valve body is a pair of spaced flanges 36 and 37 and the upper flange 36 is provided with spaced radial projections 38 which thus form 5 a series of arcuate ports between the flange proper and the wall of the inner cylinder. The lower flange 37 is provided with radial slots 39 also forming ports. In the frusto-conical chamber is a ball 40.

10 In pouring with this form of the device liquid will flow through the port 32, the valve 34 being raised, and will then pass through the slots 39 into the space between the two flanges. From there it will pass 15 through a port 41 into the hollow portion 42 of the valve and from thence into the chamber 29. From there it will flow out through the ports 30, passage 25 and ports 27 and 21.

In the form of the invention shown in Figure 9 the construction is much the same but the valve 26 is dispensed with and on the upper end of the inner cylinder portion 24 is formed an annular flange or wall 43 so that there is provided a recess or chamber 44 open 25 at the top and into this recess or chamber there extends from the diaphragm or partition 20 a pipe 45. In this form it will be seen that, just as in the other, it is impossible to manipulate the lower valve by a wire as the 30 passage is too tortuous.

In the form shown in Figures 10 and 11 the construction is somewhat different. In this form the beveled groove or notch 46, having the same purpose as the notch 14, is 35 formed in a thickened portion 47 of the bottle neck, the notch being inside of the neck. The outer casing has a body portion 48 provided with a groove 49 wherein fits a snap expansion ring 50 which, when the outer casing 40 is inserted in the bottle neck, snaps into the groove 46. Furthermore, the bottle neck fits in an annular groove 51 extending upward from the underside of a flange 52 at the top of the outer casing. The interior construction of this form is the same as that 45 illustrated in Figure 2 and the operation is alike in all cases. It will be noted that if any attempt is made to fill the bottle by placing it with its axis horizontal the ball 40 will 50 move toward the larger end of the frusto-conical part of the chamber and force the valve 34 shut.

There has thus been provided a simple and efficient device of the kind described and for 55 the purpose specified.

It is obvious that minor changes may be made in the form and construction of the invention without departing from the material spirit thereof. It is not, therefore, desired to confine the invention to the exact 60 form herein shown and described, but it is desired to include all such as properly come within the scope claimed.

Having thus described the invention, what 65 is claimed as new, is:

1. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the inner and outer casings, and an 70 upwardly opening check valve controlling the port in the lower closure of the outer casing.

2. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the inner and outer casings, said inner casing having a frusto-conical chamber in its upper end and a cylindrical chamber in its lower end 80 of greater diameter than the frusto-conical chamber, a valve in said cylindrical chamber controlling the port in the lower closure of the outer casing, and a loose ball in the frusto-conical chamber assisting in closing the last 85 mentioned valve.

3. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the inner and outer casings, said inner casing having a frusto-conical chamber in its upper end and a cylindrical chamber in its lower end of greater diameter than the frusto-conical chamber, a valve in said cylindrical chamber controlling the port in the lower closure of the outer casing, said valve consisting of a cylindrical body having a pair of spaced flanges, the lower end of the body closing said port, the lower flange having port slots therein, the body having an opening extending from its upper end downwardly and being provided with a port opening between the flanges, and a loose ball in the frusto-conical chamber assisting in closing the last mentioned valve.

4. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the in- 120

ner and outer casings, said valve consisting of a ported disk extending over the upper end of the inner casing and provided with a peripheral flange movable into and out of said space, and an upwardly opening check valve controlling the port in the lower closure of the outer casing.

5. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the inner and outer casings, said valve consisting of a ported disk extending over the upper end of the inner casing and provided 15 with a peripheral flange movable into and out of said space, said inner casing having a frusto-conical chamber in its upper end and a cylindrical chamber in its lower end of greater diameter than the frusto-conical chamber, a valve in said cylindrical chamber controlling the port in the lower closure of the outer casing, said valve consisting of a cylindrical body having a pair of spaced flanges, the lower end of the body closing said port, the lower flange having port slots therein, the body having an opening extending from its upper end downwardly and being provided with a port opening between the flanges, and a loose ball in the frusto-conical chamber assisting in closing the last mentioned valve.

10. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the inner and outer casings, said valve consisting of a ported disk extending over the upper end of the inner casing and provided 15 with a peripheral flange movable into and out of said space, said inner casing having a frusto-conical chamber in its upper end and a cylindrical chamber in its lower end of greater diameter than the frusto-conical chamber, a valve in said cylindrical chamber controlling the port in the lower closure of the outer casing, said valve consisting of a cylindrical body having a pair of spaced flanges, the lower end of the body closing said port, the lower flange having port slots therein, the body having an opening extending from its upper end downwardly and being provided with a port opening between the flanges, and a loose ball in the frusto-conical chamber assisting in closing the last mentioned valve.

15. In a non-refillable bottle, an outer cylindrical casing fitting within the neck of a bottle and immovably secured therein, said outer casing having upper and lower closures each provided with a port, an inner cylindrical casing fixed within the outer casing and having its upper end spaced from the wall of the outer casing and provided with lateral ports, a valve controlling the space between the inner and outer casings, said valve consisting of a ported disk extending over the

upper end of the inner casing and provided with a peripheral flange movable into and out of said space, said inner casing having a frusto-conical chamber in its upper end and a cylindrical chamber in its lower end of greater diameter than the frusto-conical chamber, a valve in said cylindrical chamber controlling the port in the lower closure of the outer casing, said valve consisting of a cylindrical body having a pair of spaced flanges, the lower end of the body closing said port, the lower flange having port slots therein, the body having an opening extending from its upper end downwardly and being provided with a port opening between the flanges, and a loose ball in the frusto-conical chamber assisting in closing the last mentioned valve.

20. In a non-refillable bottle having a neck provided with a mouth end, a hollow cylinder fixed in said neck and secured against removal, said cylinder having an upper end of less diameter than the lower end and closed at said upper end, said cylinder having lateral ports in the reduced end, a ported valve 60 seat at the lower end, a valve opening and closing said port, a star shaped valve between said valve and the upper part of said cylinder, an outer hollow cylinder receiving the first cylinder and locked to the neck, said 65 outer cylinder having its upper end provided with a centrally ported partition, and a valve on top of said reduced end of the inner cylinder and provided with a skirt fitting around the inner cylinder in closed position.

25. In testimony whereof we affix our signatures.
